UNITED STATES PATENT OFFICE.

FRANK E. DONALDSON, OF CHICAGO, ILLINOIS.

AIR-WASHER.

No. 910,045.

Specification of Letters Patent.

Patented Jan. 19, 1909.

Application filed April 10, 1908. Serial No. 426,282.

To all whom it may concern:

Be it known that I, FRANK E. DONALDSON, a citizen of the United States, residing at Chicago, in the county of Cook and State 5 of Illinois, have invented a new and useful Improvement in Air-Washers, of which the following is a specification.

My invention relates to that class of air washers used for cleansing, cooling, moistening and extracting moisture from air, forced into buildings for ventilating and other purposes.

The object of my invention is to provide a device through which a maximum of air 15 may pass with a minimum of friction; that will maintain a complete water curtain of spray through which all the air must pass with the least possible expenditure of mechanical energy; that provides the largest 20 proportion of surface on which the air strikes and by which the water and organic matter is eliminated from the air; that will gather the water on the eliminating surface into numerous drops or streams on which 25 the air impinges; that permits of the continued use of the same body of water; that will extract all organic matter from the water gathered from the air as it passes through the device; that will prevent any spray or 30 any uncleared air from passing through the device; that will secure a maximum of efficiency with a minimum of cost and space; and by which the temperature and humidity 35 of the air may be regulated.

The manner in which I accomplish my object is described in the following specifications and illustrated in the accompanying drawings in which:

Figure 1 is a vertical side elevation. Fig. 2 is a vertical section on the line 2-2, Fig. 3. Fig. 3 is a vertical elevation on the line 3-3, Fig. 1. Fig. 4 is an enlarged section of part of Fig. 2. Fig. 5 is an enlarged elevation of part of Fig. 3. Fig. 6 is an enlarged elevation of part of Fig. 5. Fig. 7 is a section on the line 7-7, Fig. 6. Fig. 8 is a vertical section on the line 8-8, Fig. 1. Fig. 9 is a cross section on the line 9-9, Fig. 8. Fig. 10 is a longitudinal section of 40 a spray head. Fig. 11 is a cross section on the line 11-11, Fig. 10. Fig. 12 is a sectional detail showing an extension of the structure shown in Fig. 4.

In the drawings A indicates a cement floor on which the washer rests. 55

B is a casing constituting the frame in and to which the several parts are secured and supported. This casing is of sheet metal adapted in thickness to the size and position of the device, and consists of a bottom part 60 B¹, sides B² and top B³. The front of the bottom part B¹ constitutes an open tank E adapted to hold water up to the level of the top end C of an overflow pipe C¹. This tank extends down below the level of the 65 cement floor A as shown in Figs. 1, 2 and 3. The rear edge of the bottom part B¹ forms an upward curve B⁵, as shown in Figs. 1 and 2. Supported vertically between the sides B² and on the bottom part B¹ of the 70 casing B is a series of inclined planes D, troughs D¹, gutters D² and D³. The drip points D⁴ and vertical front edge D⁵ of these planes are substantially in line with the edge of the tank E, and the vertical 75 rear edge of the planes is same distance inside of the curved edge B⁵ of the bottom B¹ of the frame as shown in Fig. 2. An enlarged section of the planes D is shown in 80 Figs. 4 and 7; enlarged face elevations in Figs. 5 and 6, and an additional form of 85 construction is shown in section in Fig. 12. These planes are constructed of sheet metal bent or joined to form the troughs D¹, gutters D² and D³ and the drip points D⁴. The 90 faces of these planes are cut so as to form apertures F and lips G. These apertures are staggered in relation to each other as shown in Figs. 5 and 6, and the lips G are bent from the face of the inclined plane as 95 shown in Fig. 7, to form vertically inclined planes as shown in Figs. 2 and 4. Connecting the troughs D¹ and gutters D³, are channels H, shown in Figs. 2 and 4 in which one side elevation and central longitudinal section is shown. These channels are located on the central vertical line and are of sufficient width to convey the overflow water from the gutters D³ to the troughs D¹ as hereinafter described. Secured to the sides 100 B² of the frame and extending forward over the top of the front half of the planes D is a deflecting plate I, the purpose of which is hereinafter described.

Supported in one of the sides B² of the 105 casing B are a series of tubes J arranged in

2

a vertical line one above the other and extending horizontally in front of the planes D and some distance therefrom as shown in section in Fig. 2 and in elevation in Fig. 3. 5 These tubes are secured in the casing as shown in Fig. 8 by lock nuts J¹ on the threaded end J² of the tubes J. Supported on the external end of each of these tubes is a union joint J³, which is locked thereon by a lock nut J⁴ and packing washer J⁵. In the union joint J³ is a nipple J⁶. Supported on this nipple is a valve K, which is connected by a nipple K¹ with a vertical pipe L. This connection is made as shown 10 in Figs. 3, 8 and 9 with attachable band connections L¹. The tube L is threaded externally at each end and is closed at the bottom by a cap L² in which a blow-off cock L³ is secured. On the top of the tube L is a 15 double elbow L⁴ having a double pipe connection L⁵ and L⁶, the purpose of which is hereinafter described.

Within the pipe L are two perforated cylinders M and N. The lower cylinder M rests 20 on the cap L² and is spaced from the interior of the tube L by the lugs O shown in Figs. 8 and 9, and is removable with the cap L². The cylinder N is fixed in the top of the tube L. This cylinder is flanged at the top N¹ to 25 fit the beveled edge of the tube L, to which it is affixed, and is tapering in its length and thereby adapted to fit in the upper end of the cylinder M as shown in Fig. 8. The lugs O are adapted to support the cylinder M at a 30 greater distance from the aperture P in the tube L than from the opposite part of the interior of the tube, to allow a free flow of water through the aperture P into the valves K. The pipe L⁵ is connected with a suitable 35 pump not shown, by which water is drawn from the tank E through the pipe L⁷ and forced through the cylinders M and N, tube L, valves K and tubes J. Supported horizontally in the tubes J are a series of spray 40 heads Q shown in elevation in Fig. 2 and in section in Figs. 10 and 11. These heads are constructed of an elongated hollow body R, having an interior cross bar R¹ and threaded hole R² therein, and supported in this hole 45 R² is a solid bell shaped head R³. The exterior of this head is so spaced from the interior of the body R as to permit a stream of water to flow therethrough as hereinafter described.

50 When the several parts are constructed as herein described and illustrated and placed in a permanent position in any structure into which air is to be forced by the use of blowers in general use, and the pipes L⁵ and L⁷ are 55 connected by a pump and the water supply turned into the tank E through the automatic valve E¹, the operation is as follows: Water is drawn from the tank E, forced through the elbow L⁴, cylinders N and M, pipe L, valves 60 K, tubes J and spray heads Q and issues in

circular sheets of spray. The spray heads being staggered in relation to each other as shown in Fig. 3, the spray therefrom intermingles and covers the whole space in front of the planes D between the sides B² of the 70 frame D, the tank E and deflector I. Through this spray all air entering the washer must pass. The air thus saturated is forced against the face and lips of the inclined planes and the water and foreign matter in the air extracted and conveyed back into the tank. Referring to Fig. 4, this process of extraction is as follows: The saturated air striking the face of the lowest plane passes up the incline and strikes the 80 underside and vertical lips of the intersecting descending plane beyond the trough D¹ and is deflected against and through the ascending plane beyond the gutter D³ and out through the rear of the washer. The air 85 which passes through the apertures F of the lowest plane is deflected downward against the baffle plate B⁶ and from there against the lips and through the apertures of the descending plane and against the baffle plate 90 B⁷, and deflected against the lips and through the apertures in the rear ascending plane. As these lips and apertures are staggered in each of the planes every particle of water and material is forced into contact with the 95 surfaces of the planes as the air is deflected upward and downward through and between the planes in the same way from the bottom to the top of the series. The spray caught and deflected by the deflector I, passes 100 through the slot I¹ in the top B³ of the frame into the trough immediately beneath and the overflow therefrom runs down the face of the ascending plane in front to the gutter at the bottom and over the front edge down the 105 drip points in drops into the gutter immediately beneath. The water collected on the rear planes flows into the gutter D³, and through the hole H¹ and channel H into the next trough at the lower end of the channel. 110 This process is duplicated in each division of the series of planes from top to bottom. The water thus extracted from the air is entrained in the troughs and gutters, and descends through the apertures and from the 115 lips and drip points in an increasing multitude of drops and streams through which the air must pass after it passes through the sheet of spray, and must thereby yield up to the water all material impurities contained 120 therein. These impurities are collected by gravitation in the tank E from which they may be passed through the pipe C¹, into the sewer, by the removal of the pipe C. All impurities which pass up through the suction 125 pipe L¹ are collected in the perforated cylinders N and M, from which they can be removed through the cock L³ or by the removal of the cap L². By passing steam through the pipe L⁶, the water used can be heated and 130

the humidity of the air, passing through the heated water be thereby increased.

It is obvious that by increasing the depth of the frame the number of inclined planes 5 may be increased and their relative forms and positions be changed as indicated by the rear planes and gutters S in Fig. 12.

What I claim and desire to secure by Letters Patent is:—

1. In an air washer of the kind described, the combination of a frame; with a series of perforated ascending and descending planes spaced vertically one above the other and affixed in said frame; a gutter connecting 15 the bases of each set of descending and ascending rear planes; a trough connecting the tops of each set of front ascending and rear descending planes; a gutter at the base of each front ascending plane and drip 20 points descending from the edge of each of said gutters; a channel affixed to each of said rear gutters and the trough adjacent thereto, adapted to conduct water from said gutter to said trough, and means adapted to produce and maintain a sheet of water spray 25 in front of said series of planes and to thereby saturate all air passing through said frame and planes, as described.

2. In an air washer, the combination with 30 a frame having a tank and deflector; of a series of inclined perforated planes spaced vertically in series and one above the other, each of said planes having pendent lips partly covering said apertures; a gutter connecting the bases of rear planes; a trough 35 connecting the tops of adjacent planes; a transverse channel connecting the rear gutter and adjacent trough adapted to conduct water from said gutter to said trough; a gutter 40 forming the front base of each front plane, a drip plate vertically pendent from each of the front gutters; and means adapted to produce and maintain a sheet of water, spray whereby all air passing through said 45 frame is saturated before it reaches said series of planes, as described.

3. In an air washer, the combination with 50 a frame and tank in the bottom thereof; of a vertical series of inclined perforated planes, each series of planes being connected longitudinally by a gutter and a trough, and the gutter above and trough below each series being connected transversely by channels adapted to conduct water from the gutter 55 to the trough, and a gutter extending longitudinally at the front of the plane in each series of planes adapted to receive the water from said plane and planes above, and to convey it in drops therefrom, and means in 60 said frame and connected therewith adapted to produce and maintain a sheet of water spray in front of said planes, as described and for the purpose specified.

4. In an air washer, the combination with 65 a frame; of a vertical series of inclined

planes and connecting gutters, troughs and channels whereby water is collected on the surface thereof and carried forward from the rear to the front of each descending series, each of said planes being cut and thereby forming apertures and pendent lips, 70 said apertures and lips being staggered in relation to each other in said planes; and means for producing and maintaining a sheet of water spray in said frame in front 75 of said planes, for the purpose described.

5. In an air washer, the combination with a frame, a vertical series of perforated inclined planes connected by gutters, troughs and channels, said series of planes being 80 affixed transversely in said frame; of a series of tubes supported in said frame horizontally in front of said planes and vertically one above the other; and a series of heads affixed in each of said tubes adapted 85 to produce a vertical sheet of water spray covering the front of said series of planes; and means connected with said tubes adapted to force a supply of water therethrough as described. 90

6. In an air washer, the combination with a frame; a series of inclined planes, connecting gutters, troughs and channels transversely and vertically affixed in said frame; and a series of tubes in said frame extending horizontally in front of said planes; of a series of heads affixed in said tubes, each of said heads consisting of a hollow longitudinal body; and a bell shaped head adjustably supported therein, said head being spaced from said body and thereby adapted to produce a vertical circular sheet of water spray, the spray from said heads completely covering the front of said series of planes in said frame, and means connected to said tubes adapted to supply and force water through said tubes and heads as described. 95

7. In an air washer, the combination with a frame, a series of inclined planes vertically and transversely affixed in said frame, 110 said planes being connected by troughs, gutters and channels whereby water collected thereon and therein is carried continually forward on said planes; and a series of horizontal tubes supported in said frame and spray heads affixed therein adapted to deliver a vertical sheet of water spray in front of said planes within said frame; of a vertical tube connecting said horizontal tubes and means in said vertical tube adapted to 115 prevent all organic material from passing into said tubes and spray heads, and means for forcing a supply of water through said tubes as described. 120

8. In an air washer; the combination with 125 a frame, a series of inclined planes vertically and transversely affixed therein, gutters, troughs and channels connecting said planes; a series of horizontal tubes supported in said frame and spray heads sup- 130

ported in said tubes, and a vertical tube connecting said horizontal tubes; of a plurality of perforated cylinders within said vertical tube and spaced therefrom, adapted to receive all water entering said tube and to prevent all foreign matter from passing through said tubes into said spray heads,

and means for forcing a supply of water through said cylinders, tubes and heads as described.

FRANK E. DONALDSON.
